UNITED STATES PATENT OFFICE.

JOHN R. CUMMINGS, OF CHICAGO, ILLINOIS, ASSIGNOR TO THE AMERICAN PRESS ASSOCIATION, OF SAME PLACE.

PRINTER'S DASH.

SPECIFICATION forming part of Letters Patent No. 329,369, dated October 27, 1885.

Application filed April 22, 1885. Serial No. 163,037. (No model.)

To all whom it may concern:

Be it known that I, JOHN R. CUMMINGS, a citizen of the United States, residing at Chicago, in the county of Cook and State of Illinois, have invented certain new and useful Improvements in Printers' Dashes; and I do hereby declare the following to be a full, clear, and exact description of the invention, such as will enable others skilled in the art to which it appertains to make and use the same.

The object of my invention is to provide a dash suitable for use with removable electro-type printing shells; and the invention consists in a dash whose beard and face are raised on a strip of thin flexible metal by a depression in the under side of said strip, the plane portions of the strip on either side of the beard and face constituting the holding-flanges, in combination with a plane-faced base-block and removable electro-type-shells.

In the use of removable electro-type-shells the base-block is so near the height of the printing-surface that a very thin dash must be used, and the flanges for holding it down in place on the block must be very low, in order that nothing but the face may give an impression. I have devised a dash of novel construction, which I find, from practical tests, answers the purposes, and one that can be easily and cheaply made.

Referring to the drawings, Figure 1 represents a perspective view of the dash. Fig. 2 is a plan view of two removable electro-type-shells mounted on a base-block and separated by my dash. Fig. 3 represents a section taken on the line $x-x$, Fig. 2. Fig. 4 is a sectional view showing the depression in the under side of the metal strip.

A denotes a strip of thin flexible metal, preferably of rectangular shape, which may be termed the "body" of the dash, from which project the beard and face B.

C represents the depression in the under side of strip A, consequent on the formation

of beard and face B. The plane portions of body A, on either side of the beard, serve as holding-flanges a.

E and F, Fig. 2, represent two removable electro-type-shells in position on a base-block, and separated by one of my dashes.

In applying the dash to the block, one of the shells is first mounted, and then one of the flanges of the dash is inserted under the end of the fixed shell, after which the other shell is clamped to the block, overlapping the other flange of the dash. The blank portions of the shells, where they overlap the flanges of the dash, are trimmed or cut away for an obvious purpose, as shown in Fig. 2, the metal of which the dash is formed being very thin, not thicker than a single sheet of ordinary news-paper, and, as the flanges usually underlie head-lines and break-lines, an apparent objection of a streaked impression has in actual practice little or no force.

To make my dash, I stamp it up from a thin sheet of brass, copper, or other suitable flexible metal; or I may take the proper impression in wax, and from this matrix take an electro-deposit.

Having thus fully described my invention, what I claim is—

The combination, with a plane-faced base-block and removable electro-type-shells, of a dash whose face and beard are raised on a strip of thin flexible metal by a depression in the under side of the strip, the plane portions of the strip on either side of the beard and face constituting the holding-flanges, which extend under the adjacent edges of the shells, by which the dash is secured in place, substantially as described.

In testimony whereof I affix my signature in presence of two witnesses.

JOHN R. CUMMINGS.
